UNITED STATES PATENT OFFICE
2,651,960
EDUCATIONAL MUSICAL INSTRUMENT
Pierre P. Pattyn, Detroit, Mich.
Application April 7, 1952, Serial No. 280,913
3 Claims. (Cl. 84—102)

1
This invention relates to an educational musical instrument.

An object of this invention is to provide a musical instrument which is designed to educate children or others in the art of music.

Another object of this invention is to provide a musical instrument embodying tone elements, and a movable web carrying interchangeable operators for the elements whereby the latter will be rendered active upon movement of said web.

A further object of this invention is to provide a musical instrument having a plurality of tone elements which may be selectively activated by a movable web or by manually operated keys.

A further object of this invention is to provide a musical instrument which can be made in great part out of plastic material.

With the above and other objects in view, my invention consists in the arrangement, combination and details of construction disclosed in the drawings and specification, and then more particularly pointed out in the appended claims.

In the drawings:

Figure 1 is a detailed side elevation of a musical instrument constructed according to an embodiment of this invention.

Figure 2 is a plan view of the instrument.

Figure 3 is a sectional view taken on the line 3—3 of Figure 2.

Figure 4 is a fragmentary sectional view taken on the line 4—4 of Figure 2.

Figure 5 is a fragmentary sectional view taken on the line 5—5 of Figure 1.

Figure 6 is a fragmentary sectional view taken on the line 6—6 of Figure 2.

Figure 7 is a fragmentary sectional view taken on the line 7—7 of Figure 1.

Figure 8 is a fragmentary sectional view taken on the line 8—8 of Figure 1.

Figure 9 is a fragmentary sectional view taken on the line 9—9 of Figure 3.

Figure 10 is a plan view partly broken away of an instruction sheet for use in positioning the operating pins embodied with the flexible web.

Figure 11 is a fragmentary sectional view through a portion of the web showing one of the removable pins.

Referring to the drawings, the numeral 15 designates generally a housing embodying oppositely disposed upright walls 16 and 17 which are secured to a base 18. A front covering 19 of relatively flexible material, such as plastic sheet material, is secured as by fastening devices 20 to the

front and upper edges of the side walls 16 and 17, respectively.

The side walls 16 and 17 are provided at their lower forward portions with extensions 21 which are adapted to be disposed at the opposite ends of the row of keys, as will be hereinafter described.

A rear covering 22 is secured by fastening means 23 to the rear of the housing 15 and includes an upper top wall member 24. There is a space 25 between the ends of the top wall members 24 and 26, the latter being an extension of the covering 19, the purpose for which will be hereinafter described.

15 A plurality of tubular tone elements 27 are suspendingly disposed within the housing 15, being suspended from cords 28 carried by a supporting bar 29 which is fixed between the side walls 16 and 17. These tubular tone elements 27 hang between horizontal and spaced apart parallel bars 30, which, at the opposite ends thereof, are secured to end bars 31 and end bars 31 are horizontally adjustable in horizontal openings 32, which are formed in the side walls 16 and 17.

20 Washer 33 is secured to each end of the rectangular frame which is formed by the parallel bars 30 so that the frame cannot shift crosswise of the housing 15. A plurality of transversely disposed cords 34 are threaded between the bars 30, as shown in Figure 5, and extend between the tubular tone elements 27 so as to keep these elements separated but, at the same time, permit these tone elements to be disposed relatively close to each other in order that these tone elements may vibrate in sympathy with each other when adjacent tone elements have been struck by the hammers, as will be hereinafter described.

25 There is a hammer 35 for each tone member 27 which is carried by an elongated resilient bar 36. The bar 36 is secured to a substantially triangular block 37, which is pivotally mounted on a horizontally disposed stationary shaft 38 which is fixed between the side walls 16 and 17. A horizontally disposed bumper bar 39 is secured 30 between the side walls 16 and 17 above the block 37, and block 37 is provided with a felt cushion member 40 adapted to contact with the bumper bar 39. A second felt member 41 is secured in the lower side 42 of block 37 and confronts the upper end of a lift bar 43, which is slidable through a horizontally disposed guide 44 fixed between the side walls 16 and 17.

35 The lift rod or bar 43 is pivotally secured at its lower end, as indicated at 45, to the inner 40 end of a key 46 which is rockable on a horizontal

shaft 47 fixed between the lower portions of the side walls 16 and 17. The keys 46, as shown in Figure 2, are arranged and formed after the manner of piano keys. It will, of course, be understood that there may be as many keys 46 as may be desired, and in the present instance, the number of keys is slightly greater than a full octave.

A felt cushion block 48 is mounted on the upper side of the bottom wall 18 below the forward end portions of the keys 46, and an inner cushion felt 49 is mounted on a horizontal supporting bar 50 disposed on the upper side of the bottom wall 18. Normally, the inner ends of the keys 46 will rest on the felt 49. The inner ends of each key 46 also have secured to the lower sides thereof a relatively thin felt 51, the purpose for which will be hereinafter described.

The structure hereinbefore described provides for the manual sounding or playing of the instrument by depressing of the keys 46 which actuates the action embodied in the pivoted blocks 31 which are rocked by the lift rods 43.

In order to provide a means whereby the instrument may be played from an endless web, I have provided a web 52 which is formed of a plurality of edge-abutting bars 53 secured together at their ends by flexible straps 54. The bars 53, as shown in Figure 11, are provided with a plurality of spaced apart threaded openings 55 within which pegs 56 are adapted to be threadably mounted. The pegs or pins 56 are arranged in such a manner, as will be hereinafter described, so that selected ones of the keys 46 will be raised and the hammers 35 will be swung inwardly to strike the tone or note members 27.

The endless web 52 is formed adjacent each end thereof with openings 57, as shown in Figure 6, within which the teeth of sprockets 58 are adapted to engage. The sprockets 58 are secured to a drive shaft 59 rotatably mounted between the side walls of the housing. A lower forward idler roll 60 is journaled across the housing 15 so that the web 54 will have a vertical inner run, as indicated at 61. The web 52 extends upwardly and rearwardly from the idler roll 60 to an intermediate idler roll 62 journaled between the side walls of the housing, and the web 52 then extends downwardly, as indicated at 63, to a lower rear idler roll 64. A web tensioning roll 65 engages the run 63 adjacent the lower end thereof so as to maintain the web substantially taut.

The web 52 extends upwardly from the rear lower roller 64, as indicated at 66, to an upper rear idler roll 67 journaled rearwardly from the drive shaft 59. The drive shaft 59 is disposed below the window opening 25 so that the pegs or pins carried by the web 52 will be exposed at the upper portion of the housing in order that these pegs or pins may be shifted about to provide for different musical selections to be played by movement of the web 52.

Drive shaft 59 has a knob 68 disposed on one end thereof, and it will be understood that if desired, a crank may be substituted for the knob 68 or a power member, such as a motor, may be operatively connected through a speed reduction means of conventional construction to the outer end of drive shaft 59.

A key lifting lever 69 is rockably mounted on a horizontally disposed fixed shaft 70 positioned at the lower portion of the housing 15, and the forward end of each lever 69 is provided with an upwardly offset extension 71 engaging be-

neath the felt 51 of a key 46 so that upward rocking of the forward end of lever 69 will effect raising of the inner end of key 46 and operation of the hammer 35. The rear end of lever 69 is pivotally secured to the lower end of an elongated lever operating rod 72, which is slidably adjacent the upper end thereof through a guide bar 73 fixed between the side walls 16 and 17.

A spring 74 is disposed about the upper portion of the rod 72, bearing at its upper end against the lower side of guide 73 and constantly urging bar 72 downwardly. A horizontally disposed lift member 75 is secured to the upper end of the lift rod 72 above the guide bar 73, and lift member 75 projects rearwardly in a position whereby lift member 75 will be contacted by a pin 56 as the web 52 rises on the forward run 61 thereof. Lift member 75 is provided with a forward projection 76 which is adapted to be engaged by a horizontally disposed rod 77, and the latter is adjustable in an inverted L-shaped slot 78 which is formed in each side wall 16 and 17, adjacent the upper portion thereof.

When rod 77 is in the upper horizontal portion of slot 78, the lift member 75 will be raised to an inoperative position, which is the position shown in Figure 3. When rod 77 is lowered to the bottom of slot 78, as shown in Figure 4, the lift members 75 will be disposed in a position to be contacted by the pins 56 and to be raised by upward movement of the pins so that rod 72 will be raised and spring 74 will be tensioned.

After a pin 56 passes and is released from lift member 75, spring 74 will move rod 72 downwardly so that lever 69 will be raised at its forward end and the key associated with the pin 56 will be raised upwardly at its rear end so that the corresponding note or tone element 24 will be sounded.

Rod 77, as shown in Figure 7, projects outwardly through the side walls of the housing so that this rod can be shifted to the upper portion of slot 78 or may be dropped to the bottom of this slot.

Referring now to Figure 10, there is disclosed a diagrammatic chart, indicated at 79, which is a diagrammatic chart of the web 52, and chart 79 has heavy dots 80 disposed thereon which are indicative of pins 56 so that looking at the chart 79, a person may adjust the pins 56 on the web 52. The upper end of the chart 79 has numbers 81 thereon which correspond to numbers 82 which are carried by a horizontally disposed bar 83 positioned at one edge of the opening 25.

In the use and operation of this device, when it is desired to play the keyboard formed by the keys 46, bar 77 is raised to the upper horizontal portion of slot 78 to the position shown in Figure 3. Depression of the keys 46 will rock the hammer carrying arms or springs 36 rearwardly so that the hammers 35 will strike the upper portions of the tubes or pipes 21.

It will be understood that the tubes or pipes 21 are merely representative of one form of a tone or note assembly and that a soundboard with strings may be mounted within the housing 15, with the strings in a position to be contacted by the hammers 35. Other forms of note or tone elements, such as the sticks of a xylophone, may be suspended within the housing 15.

When it is desired to play the instrument by movement of web 52, bar 77 is moved rearwardly in the horizontal upper portion of slot 78 and then dropped downwardly to the bottom of this slot so that the lift members 75 will be disposed

in a position to be contacted by the pins or pegs 56 carried by the web 52. As the web 52 is moved by rotation of the drive shaft 59, lift members 75 will be raised upwardly thereby raising rods 72 and tensioning springs 74. After the pin 56, which is in contact with a lift member 75, is released from the lift member, the latter, with rod 72, is moved downwardly by tensioned spring 74 so that lever 69 will be rocked upwardly at its forward end, and an associated key 46 will be raised upwardly to operative position in order to swing a hammer 35 into engagement with a tone or note element 27.

The pegs 56 can be shifted about the web 52 according to the diagram indicated on the chart 79, which is initially arranged to indicate the positions of the pins or pegs for playing of a particular musical selection.

This instrument will provide an instructive means for children or others so that the persons using the instrument will be instructed in an instrument of the percussion type.

The instrument hereinbefore described may be produced in large part out of plastic material and may be produced in varying colors of appealing characteristic which may be either transparent or opaque.

I do not mean to confine myself to the exact details of construction herein disclosed, but claim all variations falling within the purview of the appended claims.

What is claimed is:

1. A musical instrument comprising a housing, musical tone elements in said housing, rockable percussion means in said housing engageable with said elements, manually operable keys carried by said housing engaging said percussion means, an endless web, means movably supporting said web in said housing, pins carried by said web, means engageable by said pins and engaging said keys whereby to rock said keys and thereby effect operation of said percussion means, said means comprising a block member, means rockably supporting said member, a lift rod engaging said member, a key pivotally secured to said rod, a stop member limiting the rocking of said member in one direction, a hammer, and a resilient bar secured to said hammer and said member, and means for adjusting said latter named means whereby to dispose said latter named means in

50

either operative or inoperative position relative to said web.

2. A musical instrument of the percussion type comprising a housing, musical tone elements in said housing, key operated hammer means for sounding said elements, an endless web, means movably mounting said web in said housing, vertically disposed spring-pressed lift rods carried by said housing, rod lifting means carried by said web, rock levers pivotally secured to the lower ends of said lift rods and having an end thereof disposed beneath said keys whereby rocking of said levers by downward movement of said rods will rock said keys to thereby activate said first named means, and means selectively engageable with said rods to hold the same against the bias of their springs out of engagement with said hammer means.

3. A musical instrument of the percussion type comprising a housing, musical tone elements in said housing, hammer means rockably carried by said housing, a plurality of keys rockably carried by said housing, upstanding spring-biased headed hammer engaging rods pivotally carried by the inner ends of said keys, an endless web movably carried by said housing, pegs projecting from one face of said web, means in said housing engageable with said pegs to rock said keys and thereby actuate said hammer means, and manually adjustable means for rendering said latter named means inoperative, said means including an L-shaped slot in said housing and a pin projected through said slot selectively engageable with the heads of said rods to hold the same out of engagement with said hammer means.

PIERRE P. PATTYN.
